ELECTRIC APPLIANCE

Dewey M. Dow and Frederick H. Burmeister,
Toledo, Ohio, assignors to Air-Way Electric Ap-
pliance Corporation, Toledo, Ohio, a corpora-
tion of Delaware

Application February 12, 1942, Serial No. 430,678

4 Claims. (Cl. 230—117)

This invention relates to electric appliances in incorporating conductor cord reeling means, and has as its general object to provide an appliance of a type adapted to be supported in an upright position by a base in which the cord reel is embodied.

More specifically it is our object to provide an electric appliance embodying a housing the lower portion of which is provided with a base in which is embodied a cord reel so arranged as to require substantially no increase in dimensions of the said lower portion of the housing.

Another object is to provide an electric appliance embodying a cord reel which is concealed within the normal outlines of the appliance.

A further object is to provide an electric appliance adapted to be supported in an upright position and incorporating a cord reel so disposed that unreeling of the conductor cord will not unbalance the appliance.

The invention is adapted particularly to embodiment in an electric vacuum cleaner of a type having a housing adapted to be normally supported in an upright position by its base, and containing a dust collector in its upper region and a suction-blower unit in its lower region. In such a device, the above described objects of the invention are realized by utilizing a cord reel of pancake form, occupying a shallow horizontal space in the base, with its axis parallel to the main axis of the cleaner.

Another object of the invention is to provide an electric vacuum cleaner of the type described, embodying a cord reel the casing of which constitutes the bottom of the suction-blower unit compartment, with a blower outlet therein.

Another object is to provide a cord reeling mechanism embodying a novel and improved construction wherein the reel is rotatably mounted on a hollow trunnion sleeve at its center and electrical connection between the conductor cord wound upon the reel and the current consuming device, is established by brushes carried by the reel, a pair of conductor rings carried by the trunnion sleeve and contacted by the brushes, and a conductor communicating with the rings and extending through the sleeve and thence to the current consuming device.

Other and further objects of the invention will occur to those skilled in the arts to which this invention pertains as the description proceeds which, taken in connection with the accompanying drawings, sets forth a preferred embodiment and selected modifications of the invention, but such embodiment and selected modi-

fications are not to be construed as limitations of the invention but only as illustrative thereof and any and all modifications, alterations and variations of structure coming within the spirit and scope of the appended claims which limit and define the instant invention are deemed to be included herein.

In the drawings:

Fig. 1 is an inverted plan view of a vacuum cleaner embodying the invention;

Fig. 2 is a side elevation of the same, the lower region thereof being shown in section as indicated by the line 2—2 of Fig. 1;

Fig. 3 is a full size axial sectional view of the reeling device;

Fig. 4 is a horizontal view of the same, taken as indicated by the line 4—4 of Fig. 3;

Fig. 5 is a detail sectional view taken on the line 5—5 of Fig. 4;

Fig. 6 is a detail sectional view taken on the line 6—6 of Fig. 4;

Fig. 7 is a detail sectional view taken on the line 7—7 of Fig. 3, and

Fig. 8 is a detail sectional view taken on the line 8—8 of Fig. 4.

As an example of one form in which the invention may be embodied, we have shown, in the drawings, a vacuum cleaner of the general type disclosed in the pending application of Dewey M. Dow, Serial No. 412,663, filed September 27, 1941, embodying a normally upright housing 10

containing in its upper region a dust collecting and air filtering bag, and, in its lower region a suction-blower unit 12. The lower portion of the housing 10 is formed with a base skirt 14 having an outwardly extending flange 16. Secured to the flange 16 is a base ring 18 having downwardly and outwardly extending supporting legs 20 formed integrally therewith.

The suction-blower unit 12 is disposed in a blower chamber 22 within the base skirt 14, the bottom of which is defined by a stamped sheet metal bottom wall 24 having a blower outlet 26. The bottom wall 24 and flange 16 are together

secured to the underside of the base ring 18 by cap screws 28. The bottom wall 24 is formed with a central portion 30 offset upwardly to form a recess 31. The wall portion 30 forms the top wall of a reel casing 32. The casing 32 is completed by a bottom stamping 36 having a peripheral wall 38 the upper extremity of which is formed with a flange 40 secured to the recessed portion 30 of the bottom wall.

The casing 32 is substantially circular and is disposed eccentrically of the bottom wall 24 as

shown in Fig. 1, leaving a crescent shaped portion of the bottom wall projecting beyond its periphery. In a wider region of this crescent shaped projecting portion of the bottom wall is formed the blower outlet 26, adapted to receive a coupling nipple on the end of a hose.

Suspended from the center of the top wall 30 of the reel casing is a trunnion sleeve 42 on which the cord reel 44 is rotatably mounted. The sleeve 42 has a reduced, threaded upper end portion 46 which is extended through the wall 30 and provided with a nut 48 and washers 50 and 52 by means of which it is securely clamped to the wall 30. The body of the sleeve is finished exteriorly with a cylindrical trunnion surface and is received in the hub 54 of the reel 44. The lower end of the trunnion sleeve is formed with a flange 56 which supports a thrust bearing washer 58 against which the lower end of the hub 54 bears.

The reel 44 comprises a pair of discs 60 and 62, the latter having an upwardly recessed central region 64 in engagement with the disc 60 and clamped therewith between a flange 66 on the hub 54 and a washer 68 engaged by a nut 70 threaded onto the lower end of the hub 54.

The flange 66 is so located as to provide, between the top of the reel 44 and the wall 30, an annular compartment 72 in which is received a pancake coil spring 74. The spring 74 is attached at one end to the hub 54 and at its other end to the peripheral wall 38 of the casing 32, as at 76.

Secured to the lower end of the hub 46 is a current collector 78 including a pair of discs 80 and 82 of insulating material such as porcelain, for example, the disc 80 having a core portion 84 (see Fig. 4) which is received in a recess in the disc 82. A pair of screws 86 are extended through the disc 82 and the core portion 84 and threaded as at 88 into the flange 56 of the sleeve 42, thus securing the discs 80 and 82 in assembled relation to the sleeve. The flange 56 is recessed into the upper region of the disc 80 as shown. Encircling the respective discs 80 and 82 are a pair of conductor rings 90 and 92 which are formed with inturned flanges 94. The flanges 94, separated by a pair of washers 96 of insulating material, are clamped between the discs 80 and 82. Formed on the flanges 94 are a pair of terminals 98 which extend into a recess 100 in the core 84.

Electric current is carried from the terminals 98 to the motor 102 of the suction-blower unit 12 by means of a conductor 104 extending downwardly through the sleeve 46 and through a central opening in the disc 80, into the recess 100. The respective ends of the conductor 104 are connected to the terminals 98.

Current is carried to the collector 78 by a conductor cord 106 one end of which extends through an opening 108 in the peripheral wall 38 of the reel casing 32 and is provided with a connector plug 110. The intermediate portion of the cord is wrapped around the offset wall 112 which connects the recessed wall 64 to the peripheral portion of the reel disc 62. The other end of the cord is passed through an opening 114 in the offset wall 112, and clamped by a clip 116 to the inner surface of the wall 112.

Secured to the underside of the recessed wall 64 of the reel, is a bracket 118 on which is suspended a brush assembly 120. The brush assembly 120 comprises a pair of blocks 122 and 124 of insulating material, secured together and

10 to the bracket 118 by a screw 126, and a pair of brushes 128 and 130 in contact respectively with the conductor rings 90 and 92. The brushes 128 and 130 are mounted in square holes 132 in the respective blocks 122 and 124, and are urged into engagement with the rings 90 and 92 by means of coil springs 134 compressed between the brushes and the bottoms of the holes 132. The brushes 128 and 130 are connected to the cord

15 106 by short conductors 136 and bus bars 138.

From the opening 108 the cord 106 passes between a pair of pulleys 140 journaled on a bracket 142 secured to the lower side of the bottom wall 24. From the pulleys 140 the cord 15 passes between a pulley 144 and a clamp jaw 146. The jaw 146 is formed on a lever 148 which is pivoted at 150 to the bracket 142. A coil spring 152, one end of which is attached to the bracket and the other end of which is attached 20 to the lever 148, urges the jaw 146 in a direction to clamp the cord 106 against the pulley 144.

The guide pulley and clamping mechanism is accommodated in a recess 154 in the bottom wall 24, forming an extension of the recess 31. The recess 154 is located in the wider region of 25 the projecting portion of the bottom wall 24.

In using the cleaner, the cord 106 is pulled out until the desired length of cord has been unreeled. As the cord is unreeled the spring 14 30 will be coiled, storing energy by means of which it can later rotate the reel for rewinding the cord. The clamping jaw 146 will yield to permit the cord to be pulled out, but will engage the cord when the latter is released, so as to hold it against rewinding. When the operator is through using the cleaner, the cord may be rewound by simply depressing the lever 148. This releases the cord from the grip of the jaw 146 and permits the spring 14 to rotate the reel in the rewinding 40 direction.

The lever 148 is located so that it may be engaged by the toe of the operator's foot.

The invention provides a vacuum cleaner of the upright caddy type incorporating a cord reeling mechanism of ample dimensions and yet occupying a space that was formerly occupied only by the bottom wall of the suction-blower unit chamber. At the same time, the reeling mechanism is completely concealed while the cleaner is in its 45 normal upright position. The reel is of the pancake type, relatively shallow in axial dimension, so as to require a minimum axial shift of the cord during winding and unwinding. This makes it possible to bring the cord out between the guide 50 pulleys and clamping means, from which the cord issues along a fixed axis. The reel casing is embodied in the bottom wall of the cleaner, thus 55 simplifying construction and reducing cost.

The reeling mechanism, being located at the bottom of the cleaner, lowers the center of gravity thereof and thus improves the balance.

We claim as our invention:

1. In a vacuum cleaner of the upright caddy type having in its lower portion a suction-blower unit chamber, a bottom wall for said chamber, means cooperating with an eccentric area of said bottom wall to form a reel casing and leaving a substantially crescent shaped area of said bottom wall lying beyond the periphery of said casing, a blower outlet formed in said bottom wall in a wider region of said substantially crescent shaped area, and a cord reel mounted in said casing.

2. In a vacuum cleaner of the upright caddy type having in its lower portion a suction-blower

unit chamber and including a base ring having downwardly extending legs, a bottom wall for said chamber, means cooperating with said bottom wall to form a shallow reel casing disposed in a horizontal plane extending just below the plane of the lower side of said base ring and disposed eccentrically with reference to the center of said bottom wall, so as to leave an exposed substantially crescent shaped area of said bottom wall lying between one side thereof and the adjacent portion of said base ring, a blower outlet formed in said exposed area of the bottom wall, and a cord reel in said casing, said reel casing having a peripheral wall provided with an opening through which a conductor cord is adapted to issue in said horizontal plane.

3. An electric appliance including an upright housing mounted on a horizontal base having downwardly extending supporting legs, a pancake shaped cord reel mounted on said base in a horizontal plane lying just below the plane of the lower surface of said base, whereby it may deliver a conductor cord just below said base and be-

10 tween adjacent legs, said base including means forming (1) a bottom wall for said housing and (2) a casing for said reel, said casing being disposed eccentrically with reference to the center of said bottom wall so as to leave an exposed area of said bottom wall lying between one side of said casing and the periphery of said bottom wall, said housing incorporating a pressure chamber immediately above said bottom wall, and a blower outlet in said exposed area of the bottom wall.

15 4. In a vacuum cleaner of the upright caddy type having in its lower portion a suction-blower unit chamber, a bottom wall for said chamber, means cooperating with said bottom wall to form a reel casing disposed eccentrically with reference to the center of said bottom wall so as to leave an exposed area of said bottom wall lying between one side of said casing and the periphery of said bottom wall, a blower outlet in said exposed area of the bottom wall, and a cord reel in said casing.

20 DEWEY M. DOW.

FREDERICK H. BURMEISTER.
